RECOILING BARREL FIREARM WITH A
BREECH BOLT AND BREECH BOLT
CARRIER

Edwin H. Waltke, Jr., Los Angeles, Calif.

Application March 23, 1948, Serial No. 16,551

20 Claims. (Cl. 89—162)

1

My invention pertains to an improvement in recoil-barrel firearm with a branch bolt and breech bolt carrier, and more particularly to the type of automatic fire arm generally referred to as recoil-operated.

The purpose, and one of the principal objects, of this invention is to provide a rifle, or other firearm, having a more compact arrangement of parts than former firearms of this type with a resulting reduction in weight and over-all dimensions, consistent with adequate strength of design.

An important feature of this invention, in carrying out the foregoing object, is the provision of a novel mounting of the recoil-spring means, for shifting the bolt forwardly or to its firing position, and in which the spring means is positioned or confined, either when expanded or compressed, between the rear end of the receiver or barrel-supporting means and near the forward end of the bolt, or the carrier therefor, and further is located at the side of the bolt, or the axis thereof, so as not to interfere with the firing pin.

Another important object of this invention is to provide a recoil-spring means for a firearm of this class which consists of a plurality of separate springs, at least two, so that the firearm will still function if one breaks, or so that it will function properly if a lighter than a normal charge of powder is used in the shell.

A further important object of this invention is to provide a novel arrangement and construction of bolt, bolt carrier or pusher and bolt receiver whereby a compact and sturdy firearm may be made, an important feature of the invention being the provision of a novel cam means for positively operating the several elements in synchronism.

With these and other objects in view, as will appear hereinafter, I have devised a firearm having certain novel features of construction, combination, and arrangement of parts and portions, as will be hereinafter described in detail, and particularly set forth in the appended claims, reference being had to the accompanying drawings and to the characters of reference thereon, which form a part of this application, in which:

Fig. 1 is a fragmentary longitudinal sectional view of a rifle embodying, in one form, the invention of my automatic firearm, portions of the barrel and stock being broken away, dotted lines being also shown to indicate the rearward position of the bolt and bolt carrier;

Fig. 2 is a fragmentary plan view thereof, show-

2

ing portions broken away and in section to facilitate the illustration;

Fig. 3 is a transverse sectional view thereof, taken through 3—3 of Fig. 1, showing primarily the bolt in a locked position with the barrel;

Fig. 4 is a fragmentary longitudinal sectional elevational view, showing the bolt in an unlocked position from the barrel and in its initial rearwardly moving position.

Fig. 5 is a transverse sectional view, taken through 5—5 of Fig. 4, showing the adjacent ends of the bolt and barrel in their unlocked relation;

Fig. 6 is a fragmentary sectional view, taken through 6—6 of Fig. 4, showing the relation between the cams on the rear end of the bolt and the bolt receiver for rotating the bolt to effect unlocking of the bolt from the barrel;

Fig. 7 is a fragmentary longitudinal sectional view, taken through 7—7 of Fig. 6, showing the relation of cams described in Fig. 6;

Fig. 8 is a fragmentary longitudinal sectional elevational view, similar to Fig. 1 but with the bolt and bolt carrier in their rear positions within the receiver;

Fig. 9 is a transverse sectional view, showing the rear end view of the bolt and bolt carrier within the receiver;

Fig. 10 is an enlarged side view of the bolt and bolt carrier in their forward positions;

Fig. 11 is a front end view of the bolt and bolt carrier when in their forward positions;

Fig. 12 is a fragmentary longitudinal sectional view of the bolt and bolt carrier, the section being taken through 12—12 of Fig. 11; and,

Fig. 13 is a perspective view of the bolt, looking forwardly and downwardly from the right side of the bolt.

The rifle, shown in the drawings for the purpose of illustration, comprises a stock 1, having a rear butt portion 1^a and a forward portion 1^b. A receiver 2 is carried by the stock at the rear and upper portion of the forward portion 1^b of the stock. It may be secured in position by screws 3 and 4 which also secure the trigger guard or floor plate 5 to the underside of the rear of the forward portion 1^b of the stock.

The usual barrel 6 is longitudinally reciprocally mounted on the forward portion of the receiver above the forward portion 1^b of the stock and forwardly of the latter and the receiver. The barrel has a barrel guide 7 which slides in a longitudinal slot 2^a at the bottom of the forward portion of the receiver. A barrel stop pin 8 is provided on the receiver and extends across the forward portion of the slot 2^a, a spring 9 nor-

mally urging the lower portion of the guide against the pin 8. The rear end of the bore 2^b of the receiver into which the barrel 6 extends has an annular shoulder 2^c which the rear end of the barrel 6 strikes, serving as a stop upon the recoil of the barrel.

In the receiver are longitudinally reciprocally mounted the bolt 11 and bolt pusher or carrier 12, the bolt carrier being non-rotatably mounted in the receiver and the bolt 11 being rotatably and axially reciprocally mounted in the carrier. The axial movements of the bolt 11 and carrier 12 are limited to the space between the rear end of the barrel 6 and a plug 13 at the rear end of the receiver, as will be described hereinafter.

The carrier is urged to its forward position, as shown in Fig. 1, by a recoil spring means which is shown as consisting of a pair of coil springs 14 and 15. The rear ends of the springs impinge against the plug and the forward portions extend into deep longitudinal bores 12^a and 12^b in the carrier, the bores extending from the rear to near the forward ends of the carrier. Thus, the greatest practical length or space is provided for the springs 14 and 15. Guide rods 16 extend forwardly of the plug 13 into the springs and the ends of the bores to facilitate guiding of the springs when they are compressed into the bores.

When in its forward position, for locking a cartridge in the breech 6^a of the barrel, the forward end of the bolt 11 is locked to the rear end of the barrel, such locking being effected by locking lugs 11^a on the bolt and 6^b on the barrel. The locking lugs 6^b are provided on a rearward extension 6^c on the barrel. This barrel extension provides an annular recess 6^d to permit axial rotation of the forward end of the bolt. The spaces between the locking lugs 6^b of the barrel permit the locking lugs 11^a to be inserted from the rear end of the barrel to the annular recess 6^d.

The upper half of the carrier 12 is of larger diameter than the lower half and fits into a correspondingly shaped bore in the receiver, as shown in Figs. 6 and 9, thus preventing rotation of the carrier when sliding in the receiver. The bolt 11 is in a non-rotatable position with respect to the receiver 2 and the carrier 12 except when the locking lugs 11^a are located within the annular recess 6^d. The bolt is then rotated in a counterclockwise direction, when the carrier is urged forwardly by the recoil springs, by means of a cam lug 11^b on the bolt and a cam lug 12^a at the forward end of the lower portion of the carrier, as shown in Figs. 4 and 10.

Upon firing of the cartridge in the breech, the barrel 6, carrier 12, and bolt 11 are forced rearwardly, causing a cam 11^c at the rear end of the bolt to engage a helical cam 2^d at the right side of the lower portion of the bore in the receiver, and causing the bolt to be rotated in a clockwise direction to permit the locking lugs 11^a of the bolt to pass backwardly between the locking lugs 6^b of the barrel. The cam lug 11^c then moves into a longitudinal slot 2^e in the receiver below the helical cam 2^d, thereby preventing further rotation of the bolt. As the bolt is rotated in a clockwise direction the cam 11^c again engages the cam 12^d and causes the carrier 12 to move backwardly at an increased speed, both the bolt 11 and the carrier 12 moving backwardly together against the force of the recoil springs.

The rearward movement of the bolt forces the hammer 41 backwardly and causes the trigger mechanism to be cocked and the trigger 42, which is pivotally mounted about its lower end at the

rear portion of the receiver, to be forced into a cocked position by a trigger plunger 43 against the compression of a spring 44, the trigger being held in its cocked position by a sear portion 42^a on the trigger and a sear portion 43^a on the plunger 43.

As the bolt 11 moves backwardly, the extractor 21 withdraws the empty shell from the breech 6^a of the barrel opposite an open space 2^f in the receiver. In the bolt is longitudinally slidably mounted an ejector rod 22, which engages the plug 13 at the rear end of the receiver, causing the forward end of the ejector to extend beyond the forward end or face of the bolt against which the head end of the cartridge is normally seated. Such forward extension of the ejector causes projection of the empty shell to the right side of the receiver through the opening 2^f therein.

The discharge of the empty shell permits a new cartridge to be forced upwardly from the magazine 31, this magazine being shown as having a cartridge-follower 32 backed by a spring 33.

When the new cartridge is forced upwardly, the recoil springs 14 and 15 force the carrier 12 and bolt 11 forwardly, forcing the new cartridge into the chamber or breech 6^a, as described. Pulling of the trigger results in release of the hammer so that the free end thereof may strike the rear end of the firing pin 24 in the usual manner.

The following is a description of the operation of my firearm, and describes in sequence the various steps as well as co-relation and co-operation of the various elements:

A cartridge may be inserted into the breech 35 or chamber 6^a by means of a handle 17, mounted on the carrier, and extending to the right of the receiver through the opening 2^f. This may be effected by drawing the handle 17 backwardly, against the compression of the recoil springs, behind the rear end of a new cartridge forced upwardly from the magazine. Forward movement of the handle, or automatic action of the springs, causes the cartridge to be forced into the breech or chamber 6^a.

Assuming the cartridge to be in firing position, the gun is now ready to fire, which is effected by pulling the trigger 42 backwardly. This permits the firing spring 44 to force the plunger 43 forwardly and force the hammer 41 forwardly until it strikes the rear end of the firing pin knob 23 provided at the rear end of the firing pin 24 which extends through the axial portion of the bolt, and forces the forward end of the firing pin beyond the forward end of the bolt against which the head of the cartridge rests, as shown best in Fig. 12. The cartridge is thus fired.

Upon the explosion of the cartridge, the barrel, carrier, and bolt are recoiled rearwardly with respect to the receiver 2, as described above. As the cam 11^c engages the helical cam 2^d on the receiver, the bolt and carrier are unlocked from the barrel. The recoil of the barrel is limited by the annular shoulder 2^c at the rear of the bore 2^b. The spring 9 then returns the barrel to its initial or normal forward position.

Simultaneously with the clockwise rotation of the bolt, effected by the engagement of the cams 11^c and 2^d, another camming action takes place 70 between the cams 11^b and 12^d, which causes the bolt carrier to move backwardly at a greater speed than the bolt, as described above, both the carrier and the bolt, however, continuing backwardly together due to their own momentum, the recoil of both of these elements being grad-

ually absorbed by the springs 14 and 15. The remaining energy of these two members is absorbed by the receiver plug 13. At this point the spent cartridge case or shell is ejected, as stated. Shortly after the beginning of the forward movement of the carrier by the recoil springs, the face of the bolt 11 engages the edge of a new cartridge which is forced by the bolt into the chamber or breech of the barrel. As the face of the bolt strikes the rear of the barrel at 6^a, the bolt carrier continues forwardly a short distance, and during the latter movement a rotary action takes place between the cams 11^b and 12^d causing the bolt to be rotated in a counterclockwise direction, causing the lugs 11^a at the forward end of the bolt to be locked behind the lugs 6^b on the barrel. Thus the cartridge is locked into position to be discharged when the trigger is pulled.

One of the essential features of my invention is that the spring means, consisting of a spring or springs, returning the bolt assembly to the firing position and causing the locking of the breech, is or are so mounted that it or they impinge upon the locking means, or one of the elements thereof, which, in this instance, is the bolt pusher or carrier, at a point near the front end of the bolt. Therefore when the bolt and locking means thereof recoil rearwardly and the rear end of the bolt strikes the plug or stop in the receiver, an appreciable space is provided between the rear end of the bolt and the point of impingement of the spring or springs upon the locking means. Therefore no space is necessary or provided between the rear end of the bolt and the bolt stop. This construction results in the advantage of a more compact arrangement of the working members.

I wish it to be understood that I do not desire to be limited to the exact details of construction shown and described, for obvious modifications will occur to a person skilled in the art.

I claim:

1. A firearm operated by recoil, comprising a supporting means, a barrel longitudinally reciprocally mounted on the supporting means, a bolt carrier longitudinally reciprocally mounted on the supporting means at the rear end of and longitudinally shiftable with respect to the barrel, a bolt mounted in the carrier and longitudinally shiftable with respect thereto, said carrier having an opening extending from its rear end to near the forward end, and a recoil spring positioned with its forward portion in the opening and its rear end bearing against the supporting means.

2. A firearm operated by recoil, comprising a barrel, a receiver reciprocally supporting the rear end portion of the barrel, a bolt carrier longitudinally reciprocally mounted within the receiver at the rear end of and longitudinally shiftable with respect to the barrel, a bolt mounted in the carrier and longitudinally shiftable with respect thereto, said carrier having an opening extending from its rear end to near the forward end, and a recoil spring positioned with its forward portion in the opening and its rear end bearing against the rear end portion of the receiver.

3. A firearm operated by recoil, comprising a supporting means, a barrel longitudinally reciprocally mounted on the supporting means, a bolt carrier longitudinally reciprocally mounted on the supporting means at the rear end of and longitudinally shiftable with respect to the bar-

rel, a bolt mounted in the carrier and longitudinally shiftable with respect thereto, said carrier having openings extending from its rear end to near the forward end, and a plurality of recoil springs positioned with their forward portions in the openings and their rear ends bearing against the supporting means.

4. A firearm operated by recoil, comprising a barrel, a receiver reciprocally supporting the rear end portion of the barrel, a bolt carrier longitudinally reciprocally mounted within the receiver at the rear end of and longitudinally shiftable with respect to the barrel, a bolt mounted in the carrier and longitudinally shiftable with respect thereto, said carrier having openings extending from its rear end to near the forward end, and a plurality of recoil springs positioned with their forward portions in the opening and their rear ends bearing against the rear end portion of the receiver.

5. A firearm operated by recoil, comprising a supporting means, a barrel longitudinally reciprocally mounted on the supporting means, a bolt carrier longitudinally reciprocally and non-rotatably mounted on the supporting means at the rear end of and longitudinally shiftable with respect to the barrel, a bolt rotatably mounted in the carrier and longitudinally shiftable with respect thereto, and a recoil spring positioned with its forward end against the carrier and its rear end bearing against the supporting means.

6. A firearm operated by recoil, comprising a barrel, a receiver reciprocally supporting the rear end portion of the barrel, a bolt carrier longitudinally reciprocally and non-rotatably mounted within the receiver at the rear end of and longitudinally shiftable with respect to the barrel, a bolt rotatably mounted in the carrier and longitudinally shiftable with respect thereto, and a recoil spring positioned with its forward end against the carrier and its rear end bearing against the rear portion of the receiver.

7. A firearm operated by recoil, comprising a supporting means, a barrel longitudinally reciprocally mounted on the supporting means, a bolt carrier longitudinally reciprocally and non-rotatably mounted on the supporting means at the rear end of and longitudinally shiftable with respect to the barrel, a bolt rotatably mounted in the carrier and longitudinally shiftable with respect thereto, and a plurality of recoil springs positioned with their forward ends against the carrier and their rear ends bearing against the supporting means.

8. A firearm operated by recoil, comprising a barrel, a receiver reciprocally supporting the rear end portion of the barrel, a bolt carrier longitudinally reciprocally and non-rotatably mounted within the receiver at the rear end of and longitudinally shiftable with respect to the barrel, a bolt rotatably mounted in the carrier and longitudinally shiftable with respect thereto, and a plurality of recoil springs positioned with their forward ends against the carrier and their rear ends bearing against the rear end portion of the receiver.

9. A firearm operated by recoil, comprising a supporting means, a barrel longitudinally reciprocally mounted on the supporting means, a bolt carrier longitudinally reciprocally mounted on the supporting means at the rear end of and longitudinally shiftable with respect to the barrel, a bolt mounted in the carrier and longitudinally shiftable with respect thereto, said carrier having an opening extending from its rear end

to near the forward end, a recoil spring positioned with its forward portion in the opening and its rear end bearing against the supporting means, means for rotating the bolt and locking the same to the rear end of the barrel at the instant of firing, means automatically disconnecting the bolt from the barrel upon the recoil of the latter, and means to check the recoil of the barrel.

10. A firearm operated by recoil, comprising a barrel, a receiver reciprocally supporting the rear end portion of the barrel, a bolt carrier longitudinally reciprocally mounted within the receiver at the rear end of and longitudinally shiftable with respect to the barrel, a bolt mounted in the carrier and longitudinally shiftable with respect thereto, said carrier having an opening extending from its rear end to near the forward end, a recoil spring positioned with its forward portion in the opening and its rear end bearing against the rear end portion of the receiver, means for rotating the bolt and locking the same to the rear end of the barrel at the instant of firing, means automatically disconnecting the bolt from the barrel upon the recoil of the latter, and means to check the recoil of the barrel.

11. A firearm operated by recoil, comprising a supporting means, a barrel longitudinally reciprocally mounted on the supporting means, a bolt carrier longitudinally reciprocally and non-rotatably mounted on the supporting means at the rear end of and longitudinally shiftable with respect to the barrel, a bolt rotatably mounted in the carrier and longitudinally shiftable with respect thereto, a recoil spring positioned with its forward end against the carrier and its rear end bearing against the supporting means, means for rotating the bolt and locking the same to the rear end of the barrel at the instant of firing, means automatically disconnecting the bolt from the barrel upon the recoil of the latter, and means to check the recoil of the barrel.

12. A firearm operated by recoil, comprising a barrel, a receiver reciprocally supporting the rear end portion of the barrel, a bolt carrier longitudinally reciprocally and non-rotatably mounted within the receiver at the rear end of and longitudinally shiftable with respect to the barrel, a bolt rotatably mounted in the carrier and longitudinally shiftable with respect thereto, a recoil spring positioned with its forward end against the carrier and its rear end bearing against the rear portion of the bolt, means for rotating the bolt and locking the same to the rear end of the barrel at the instant of firing, means automatically disconnecting the receiver from the barrel upon the recoil of the latter, and means to check the recoil of the barrel.

13. A firearm operated by recoil, comprising a supporting means, a barrel longitudinally reciprocally mounted on the supporting means, a bolt carrier longitudinally reciprocally mounted on the supporting means at the rear end of and longitudinally shiftable with respect to the barrel, a bolt mounted in the carrier and longitudinally shiftable with respect thereto, said carrier having an opening extending from its rear end to near the forward end, and a recoil spring positioned with its forward portion in the opening and its rear end bearing against the supporting means, said spring being compressible, upon the recoil of the carrier, substantially into said opening.

14. A firearm operated by recoil, comprising a

5 barrel, a receiver reciprocally supporting the rear end portion of the barrel, a bolt carrier longitudinally reciprocally mounted within the receiver at the rear end of and longitudinally shiftable with respect to the barrel, a bolt mounted in the carrier and longitudinally shiftable with respect thereto, said carrier having an opening extending from its rear end to near the forward end, and a recoil spring positioned with its forward portion in the opening and its rear end bearing against the rear end portion of the receiver, said spring being compressible, upon the recoil of the carrier, substantially into said opening.

15. A firearm operated by recoil, comprising a supporting means, a barrel longitudinally reciprocally mounted on the supporting means, a bolt carrier longitudinally reciprocally mounted on the supporting means at the rear end of and longitudinally shiftable with respect to the barrel, a bolt mounted in the carrier and longitudinally shiftable with respect thereto, said carrier having an opening extending from its rear end to near the forward end, and a plurality of recoil springs positioned with their forward portions in the openings and their rear ends bearing against the supporting means, said springs being compressible upon the recoil of the carrier, substantially into said openings.

20 16. A firearm operated by recoil, comprising a barrel, a receiver reciprocally supporting the rear end portion of the barrel, a bolt carrier longitudinally reciprocally mounted within the receiver at the rear end of and longitudinally shiftable with respect to the barrel, a bolt mounted in the carrier and longitudinally shiftable with respect thereto, said carrier having an opening extending from its rear end to near the forward end, and a plurality of recoil springs positioned with their forward portions in the openings and their rear ends bearing against the rear end portion of the receiver, said springs being compressible, upon the recoil of the carrier, substantially into said openings.

25 17. A firearm operated by recoil, comprising a supporting means, a barrel longitudinally reciprocally mounted on the supporting means, a bolt carrier longitudinally reciprocally mounted on the supporting means at the rear end of the barrel, a bolt mounted in the carrier and longitudinally shiftable with respect thereto, and a recoil spring positioned with its forward end against the carrier and its rear end bearing against the supporting means, said spring being compressible, upon the recoil of the barrel and the carrier, into a space surrounding the longitudinal axis of the bolt.

30 18. A firearm operated by recoil, comprising a barrel, a receiver reciprocally supporting the rear end portion of the barrel, a bolt carrier longitudinally reciprocally mounted within the receiver at the rear end of the barrel, a bolt mounted in the carrier and longitudinally shiftable with respect thereto, and a recoil spring positioned with its forward end against the carrier and its rear end bearing against the rear end portion of the receiver, said spring being compressible, upon the recoil of the barrel and the carrier, into a space surrounding the longitudinal axis of the bolt.

35 19. A firearm operated by recoil, comprising a supporting means, a barrel longitudinally reciprocally mounted on the supporting means, a bolt carrier longitudinally reciprocally and non-rotatably mounted on the supporting means at the rear end of and longitudinally shiftable with respect to the barrel, a bolt rotatably mounted in

the carrier and longitudinally shiftable with respect thereto, a recoil spring positioned with its forward end against the carrier and its rear end bearing against the supporting means, mating cams at the forward portions of the carrier and the bolt for rotating the latter and locking the forward end thereof to the rear end of the barrel at the instant of firing, other mating cams on the rear portion of the bolt and the supporting means for rotating the bolt in the opposite direction a distance sufficient only automatically to disconnect the bolt from the barrel upon the recoil of the same, and means to check the recoil of the barrel upon the disconnection of the bolt therefrom, the first cams reengaging each other, simultaneously with the disconnection of the bolt from the barrel, to increase the rearward movement of the carrier.

20. A firearm operated by recoil, comprising a barrel, a receiver reciprocally supporting the rear end portion of the barrel, a bolt carrier longitudinally reciprocally and non-rotatably mounted within the receiver at the rear end of and

5 longitudinally shiftable with respect to the barrel, a bolt rotatably mounted in the carrier and longitudinally shiftable with respect thereto, a recoil spring positioned with its forward end against the rear portion of the receiver, mating cams at the forward portions of the carrier and the bolt for rotating the latter and locking the forward end thereof to the rear end of the barrel at the instant of firing, other mating cams on the rear portion of the bolt and the receiver for rotating the bolt in the opposite direction a distance sufficient only automatically to disconnect the bolt from the barrel upon the recoil of the same, and means to check the recoil of the barrel upon the disconnection of the bolt therefrom, the first cams reengaging each other, simultaneously with the disconnection of the bolt from the barrel, to increase the rearward movement of the carrier.
